SKELTON D. HENRY, OF HOUSTON, TEXAS

MEANS FOR PROTECTING DAMS

Application filed June 29, 1928. Serial No. 289,269.

This invention relates to dams, and is more particularly concerned with a method of and means for protecting the same against rupturing crevasses and excessive seepage.

5 The pressure of the head of water impounded by the dam wall against the small crevasses or cracks which form in the walls of dams is, in the case of large dams, so tremendous that the crevasse, unless protected, will gradually be enlarged to the rupture point.

Excessive seepage of water through and beneath the base of the dam walls will ultimately undermine the foundations, and weaken the dam to the danger point. This is especially true and the liability of rupture is proportionately great in the cases of dam walls impounding large volumes of water which exert tremendous pressure and by reason of this pressure augment the penetration 20 of the water and resultant seepage.

A feature of the invention is the method of and means for caulking crevasses and preventing rupture of the dam wall which consists in facing the reservoir side of the dam 25 wall with a flexible apron of caulking material which may advantageously consist of matted fiber anchored to the dam wall.

A further feature of the invention consists in the method of and means for automatically caulking crevasses and preventing excessive seepage which consists in facing the reservoir side of the dam wall and the adjacent floor of the reservoir with a flexible apron 30 of matted fiber, such as creosote impregnated excelsior, having the function of caulking crevasses developing in the face of the dam wall and of penetrability by silt to form a protective flooring or facing resisting and reducing seepage.

40 The invention as developed in detail will be more clearly apparent from the following detailed specification which is to be read in conjunction with the accompanying drawings forming part thereof and in which:—

45 Figure 1 is a transverse vertical section through a dam wall and reservoir floor showing the method of and means for protection against rupturing crevasses and seepage.

50 Figure 2 is a vertical section on an enlarged scale through the upper portion of the dam

wall and its facing showing the manner of anchoring the apron of matted fiber to the dam wall, the overlying solid protective sheathing at the upper edge of the apron and the overlying silt penetrable screening therebelow.

55 Figure 3 is a fragmentary horizontal section through a portion of the dam wall and flexible fiber apron illustrating the crevasse caulking or plugging action of the apron fiber under pressure of the impounded water head.

The wall 1 of the dam which, as shown, is of concrete and of the conventional triangular type has its inner or reservoir face 2 protected by an apron 3 of matted fibrous material, preferably matted excelsior impregnated with creosote or other preservative and extending from the upper edge of the dam wall 1 downwardly over its reservoir face 2 and over the adjacent floor of the reservoir to which it is anchored by suitable superposed weights such as large rock, scrap iron or concrete. This apron of fiber is anchored to the reservoir face of the dam wall by means of a series of hooks 5 having their shanks imbedded in the wall 1 and their hooked ends imbedded in the mat of fiber. The face of the upper end of the apron is protected against damage by débris, ice, etc., floating on the surface of the impounded water by means of a solid protective sheathing strip 6 suitably anchored to the face of the apron and supported by appropriate means such as the underlying ends of long hooked rods 7 similar to but of greater length than the anchoring hooks 5 and similarly imbedded in the dam wall.

80 From the lower edge of the solid sheathing 6 downwardly to and over the apron overlying the adjacent reservoir floor, the face of the apron is overlaid by a flexible permeable sheathing such as galvanized wire netting 8, permitting penetration of the apron mat by the impounded water and the filling of the interstices of the fiber by silt to form a layer or apron resisting the seepage of water therethrough, thereby preventing excess seepage.

85 The fibrous mat 3 with its overlying netting or sheathing screen 8 forms a flexible apron,

100

the fibrous material constituting an effective caulk or crevasse plugging material. In the event, crevasses such as indicated at 9 in Figure 3, form in the face of the dam wall, the pressure of the head of the impounded water against the flexible apron will force the fibrous material of the apron into the crevasses or cracks 9, automatically caulking or plugging the same as suggested in Figure 3. The silt deposited in and serving to fill up the interstices of the fibers will act also to shield the crevasse or crack against the pressure head of the impounded water and will cooperate with the fiber forced in the crevasse effectively to plug the opening.

15 The material of the protective apron may vary within reasonably wide limits. I have specifically noted excelsior protected and indurated by creosote or similar impregnation 20 since this material is readily obtained and treated and may be obtained in the large quantities needed for this work. Other materials of a fibrous nature which may be given indurating treatment and matted to form a 25 protective flexible apron, may of course, be used in lieu of excelsior. Such a fiber mat may easily be forced into a crevasse by the pressure head of the impounded water and is aided by the mud and silt deposited therein 30 by the water to effectively caulk crevasses and cracks as they are formed in the dam wall.

What I claim therefore and desire to secure by Letters Patent is:

35 1. A water retaining wall having a flexible apron of matted excelsior overlying the water face thereof and anchored to said wall and to the adjacent floor of the water bed, and a sheathing plate extending across the upper 40 edge of the apron and protecting the same against injury by floating débris.

45 2. A water retaining wall having a flexible apron of matted excelsior overlying the water face thereof and covered by an overlaid flexible metallic netting permeable by water and silt and anchored to said wall and to the adjacent floor of the water bed to retain the apron against the wall face, and a solid protective sheathing strip extending across and 50 held against the top of said apron to protect the same against damage by floating débris.

SKELTON D. HENRY.
